Primary Examiner — Melody N Brown*(74) Attorney, Agent, or Firm* — Global IP Counselors, LLP(57) **CLAIM**

The ornamental design for a front bumper for an automobile, as shown and described.

DESCRIPTION

FIG. 1 is a front elevational view of a front bumper for an automobile showing our new design;

FIG. 2 is a top plan view thereof;

FIG. 3 is a bottom plan view thereof;

FIG. 4 is a right side elevational view thereof;

FIG. 5 is a left side elevational thereof;

FIG. 6 is a top, front and right side perspective view thereof; and,

FIG. 7 is a bottom, front and left side perspective view thereof.

The rear view of the front bumper forms no part of the claimed design.
